UNITED STATES PATENT OFFICE.

FRANK R. GREENE, OF CHICAGO, ILLINOIS.

DESIGN FOR A CASING FOR A VENDING-MACHINE.

56,251.

Specification for Design.

Patented Sept. 7, 1920.

Application filed January 12, 1920. Serial No. 351,055. Term of patent 14 years.

To all whom it may concern:

Be it known that I, FRANK R. GREENE, a citizen of the United States, residing at Chicago, in the county of Cook and State of Illinois, have invented a new, original, and ornamental Design for Casings for Vending-Machines, of which the following is a specification, reference being had to the accompanying drawing, forming part thereof, which shows a perspective view of the design.

The figure is a perspective view of a casing for a vending machine showing my new design.

I claim:

The ornamental design for a casing for a vending machine as shown.

FRANK R. GREENE.
